B. Erbe,
 Reversible Latch,
 No 59,373, Patented Nov. 6, 1866.

Barthel Erbe

UNITED STATES PATENT OFFICE.

BARTHEL ERBE, OF PITTSBURG, PENNSYLVANIA.

IMPROVEMENT IN DOOR-LATCHES.

Specification forming part of Letters Patent No. 59,373, dated November 6, 1866.

To all whom it may concern:

Be it known that I, BARTHEL ERBE, of the city of Pittsburg, State of Pennsylvania, have invented certain new and useful Improvements in the manner of Constructing Door Latches; and I hereby declare that the following is a full and exact description of the same, reference being had to the accompanying drawings, and to the letters of reference marked thereon, which form part of this specification.

My invention consists in so connecting the lever, which operates the latch-bolt with the case or frame that the pivotal point or center of motion of said lever may be moved or adjusted so as to allow the latch-head to protrude from the case sufficiently to permit its being revolved on its axis without being disconnected from the other parts of the latch.

The object of my invention is to adapt a beveled latch-head to use in a lock-case for a right or left hand door.

In the drawings, Figure 1 represents a plan of the internal arrangement of an ordinary lever-latch embodying my improvements, with the various parts in position for use. Fig. 2 represents the same plan with the lever adjusted so as to permit the latch-head to protrude beyond the case sufficiently to allow its being revolved on its axis.

The same letters refer to the same parts in all the figures.

a is the case or frame. *b* is the latch-bar. It has a square head, *b'*, which is beveled on one side, as ordinary latches are, the shaft of the latch being round at *b* and smaller than the square hole through which it protrudes. The latch is connected at *w* by a swivel-joint to the lever *c*, which is operated by an ordinary hub or follower, *d*. The lever *c*, which chiefly involves my invention, is connected with the case at the pin *e*, which passes through the oval hole *f*.

In the position shown in Fig. 1 the pivotal point or fulcrum of lever *c* is between the lever and the sliding rest or stopper *g*, which has an independent motion and is operated by

the handle *h*, which projects through the opening *o* in the edge of the case. Ordinarily this slide is used as a stopper to prevent the movement of the latch, which it accomplishes when brought into the position indicated by the dotted lines *i j* in Fig. 1, the part *g* being large enough to still support the end of the lever when the part *i* comes in contact with the point of lever marked *s*.

When it is desired to reverse the latch the supplemental stopper *i* is forced inside of the case by pressing on the point *v*, so as to allow sufficient movement to the entire slide *g* to withdraw it entirely from the support of the lever *c*, as shown in Fig. 2. The spiral spring *x* immediately throws the latch forward so as to protrude the head, as shown at *b'*, Fig. 2, in which position it may be reversed from the right to the left, as shall be desired.

To restore it to its working position it is only necessary to push lightly on the end of the latch, so as to hold it in the square opening, and then by the handle *h* pull the slide *g* back to the position shown in Fig. 1, when the spring indicated by dotted line *k* will force the supplemental side *i* back to its position, and the point *v* will project through the case by the side of the handle *h* and prevent the accidental displacement of *g* from its proper working position.

Although I have described this slide thus particularly, I do not consider it an essential part of my invention, as its form may be variously modified, or it may be displaced entirely and the lever held in its position by the presence of a screw or some other movable part.

I therefore claim as my invention and desire to secure by Letters Patent—

So connecting the lever *c* with the case or frame, that it may have the supplemental motion and adjustment herein described, substantially for the purpose set forth.

BARTHEL ERBE.
